CASE END CAP FOR PHOTOGRAPHIC SCREENS

Frank D. Sayer and Donald E. Browne, Warsaw, Ind.,
assignors to Da-Lite Screen Company, Inc., Warsaw,
Ind., a corporation of Illinois

Filed Nov. 4, 1960, Ser. No. 62,761

Term of patent 14 years

(CL. D61—1)

FIG.1

Figure 1 is a perspective view of a case end cap for photographic screens showing our new design.

Fig. 2 is a top plan view thereof.

Fig. 3 is a bottom plan view.

Fig. 4 is a side view.

Fig. 5 is a cross-sectional view taken on line 5—5 of Fig. 2.

We claim:

The ornamental design for a case end cap for photographic screens, as shown.
